CLAIM

The ornamental design for a configurable chess board as shown and described.

DESCRIPTION

FIG. 1 is a top perspective view of a configurable chess board embodying my design.

FIG. 2 is a top plan view thereof.

FIG. 3 is a bottom plan view thereof.

FIG. 4 is an elevational view of one side thereof, the other three sides being identical.

FIG. 5 is an exploded perspective view thereof.

FIG. 6 is an enlarged perspective view of one of the tiles thereof.

FIG. 7 is a top plan view, similar to FIG. 2, of an alternative embodiment of this invention having indicia provided on each of the tiles thereof; and,

FIG. 8 is a partially exploded perspective view thereof.
